(57) **CLAIM**

The ornamental design for an assistive cup, as shown and described.

DESCRIPTION

FIG. 1 is a top, front perspective view showing an embodiment of the assistive cup of Applicant's new design.

FIG. 2 is a front elevation view of the assistive cup of FIG. 1.

FIG. 3 is a rear elevation view of the assistive cup of FIG. 1.

FIG. 4 is a left-side elevation view of the assistive cup of FIG. 1.

FIG. 5 is a right-side elevation view of the assistive cup of FIG. 1.

FIG. 6 is a top plan view of the assistive cup of FIG. 1.

FIG. 7 is a bottom plan view of the assistive cup of FIG. 1.

FIG. 8 is a top, perspective view showing another embodiment of the assistive cup of Applicant's new design.

FIG. 9 is a front elevation view of the assistive cup of FIG. 8.

FIG. 10 is a rear elevation view of the assistive cup of FIG. 8.

FIG. 11 is a left-side elevation view of the assistive cup of FIG. 8.

FIG. 12 is a right-side elevation view of the assistive cup of FIG. 8.

FIG. 13 is a top plan view of the assistive cup of FIG. 8.

FIG. 14 is a bottom plan view of the assistive cup of FIG. 8.

FIG. 15 is a top, perspective view showing another embodiment of the assistive cup of Applicant's new design.

FIG. 16 is a front elevation view of the assistive cup of FIG. 15.

FIG. 17 is a rear elevation view of the assistive cup of FIG. 15.

FIG. 18 is a left-side elevation view of the assistive cup of FIG. 15.

FIG. 19 is a right-side elevation view of the assistive cup of FIG. 15.

(Continued)

FIG. 20 is a top plan view of the assistive cup of FIG. 15; (56)

and,

FIG. 21 is a bottom plan view of the assistive cup of FIG. 15.
